UNITED STATES PATENT OFFICE.

JOSEPH HERMAN SANDELL, OF CHICAGO, ILLINOIS, ASSIGNOR TO COMSTOCK-CASTLE STOVE COMPANY, OF QUINCY, ILLINOIS, A CORPORATION OF ILLINOIS.

DESIGN FOR A HEATER.

Application filed February 1, 1929. Serial No. 29,875. Term of patent 14 years.

To all whom it may concern:

Be it known that I, JOSEPH HERMAN SANDELL, a citizen of the United States, residing at Chicago, in the county of Cook and State of Illinois, have invented a new, original, and ornamental Design for Heaters, of which the following is a specification, reference being had to the accompanying drawing, forming part thereof.

In the drawing the figure is a perspective view of the heater showing my new design.

I claim:

The ornamental design for a heater, as shown.

JOSEPH HERMAN SANDELL.
